UNITED STATES PATENT OFFICE

152,943

DESIGN FOR A FILE HOLDER

George T. Conarton, Lansing, Mich.

Application January 17, 1947, Serial No. 136,221

Term of patent 14 years

(Cl. D54—13)

To all whom it may concern:

Be it known that I, George T. Conarton, a citizen of the United States, residing at Lansing, in the county of Ingham and State of Michigan, have invented a new, original, and ornamental Design for File Holders, of which the following is a specification, reference being had to the accompanying drawings, forming part thereof.

Fig. 1 is a side elevation of a file holder showing my new design.

Fig. 2 is a top view thereof.

Fig. 3 is a bottom view of the same.

Fig. 4 is a rear view.

I claim:

The ornamental design for a file holder, as shown.

GEORGE T. CONARTON.
